(Cl. D1—12)

To all whom it may concern:

Be it known that I, Kenneth F. Smith, a citizen of the United States, residing at Lima, Allen County, State of Ohio, have invented a new, original, and ornamental Design for a Sign or Similar Article, of which the following is a specification, reference being had to the accompanying drawings, forming part thereof. In the drawings,

Figure 1 is a view in front elevation of a sign or similar article, showing my new design; the opposite side is similar;

Fig. 2 is a top view; the bottom is similar; and

Fig. 3 is a view in end elevation, both ends being similar.

I claim:

The ornamental design for a sign or similar article, as shown.

KENNETH F. SMITH.
